UNITED STATES PATENT OFFICE.

BASIL V. SZABÓ, OF CHICAGO, ILLINOIS, ASSIGNOR OF TWO-THIRDS
TO FERDINAND SIEGEL AND JOSEPH ALEXANDER, OF CHICAGO,
ILLINOIS.

MOTOR.

SPECIFICATION forming part of Letters Patent No. 716,143, dated December 16, 1902.

Application filed March 5, 1901. Serial No. 49,833. (No model.)

To all whom it may concern:

Be it known that I, BASIL V. SZABÓ, of Chicago, in the county of Cook and State of Illinois, have invented certain new and useful 5 Improvements in Motors; and I do hereby declare that the following is a full, clear, and exact description thereof, reference being had to the accompanying drawings, and to the letters of reference marked thereon, which form 10 a part of this specification.

This invention relates to improvements in rotary engines or motors; and it consists in the matters hereinafter described, and pointed out in the appended claims.

15 My invention is shown in connection with two different general forms of rotary engines—one in which the exterior casing or inclosure of the engine is rotative and the interior part thereof, through which steam is supplied to the 20 interior of the casing, is stationary, and another construction, the reverse of that referred to, wherein the said exterior part or casing is stationary and the interior part is adapted to rotate.

25 My invention will be more readily understood by reference to the accompanying drawings, wherein—

Figure 1 is a view in side elevation of a motor embodying my invention of that kind in 30 which the exterior casing of the motor turns or rotates. Fig. 2 is a central vertical section thereof, taken on the plane of the shaft. Fig. 3 is a vertical section taken on the line 3 3 of Fig. 2. Fig. 4 is a detail section taken 35 on line 4 4 of Fig. 2. Fig. 5 is a plan section taken on line 5 5 of Fig. 3. Figs. 6 and 7 are side or face views of the radially-movable piston of the engine shown in Figs. 2 and 3. Fig. 8 is a view showing, in side elevation, the 40 two separable parts of such piston. Fig. 9 is a sectional view taken on line 9 9 of Fig. 8. Fig. 10 is a side view of the shoe belonging to the piston shown in Fig. 8. Fig. 11 is a plan view of the same. Fig. 12 is a cross-sectional view taken on line 12 12 of Fig. 11. Fig. 13 is a cross-sectional view taken on line 13 13 of Fig. 11. Fig. 14 is a view in side elevation of still another form of piston. Fig. 15 is a sectional view taken on line 15 15 of 45 Fig. 14. Fig. 16 is a sectional view taken on line 16 16 of Fig. 14. Fig. 17 is a detail sec-

tional view showing one of the lateral extensions of the valve-casings to receive the sliding piston. Fig. 18 is a cross-section of the same, taken on line 18 18 of Fig. 17. Fig. 19 55 is a view, with parts in section, of two motors acting on a common rotative shaft, said motors having stationary casings and being connected so as to operate as a compound engine. Fig. 20 is a view showing one of the 60 motors of Fig. 19 in side elevation and the parts in section, taken on line 20 20 of said Fig. 19. Fig. 21 is a sectional view taken on line 21 21 of Fig. 19. Fig. 22 is a detail section taken on line 22 22 of Fig. 19. 65

As shown in said drawings, Figs. 1 to 7, A indicates the exterior casing of the engine, which is rotative and mounted upon stationary spindles B, which may be sustained in a horizontal position by any suitably-arranged 70 support or supports, but which, as herein shown, is mounted at its ends on standards C C, attached to a floor or suitable base or support. The casing A is shown as having attached thereto, concentric therewith, a belt-pulley D, 75 through which motion may be transmitted from the motor by a suitable belt. Said casing A is shown as consisting of a hollow cylinder A', with which the belt-pulley D is herein shown as cast integral, and two flat 80 heads A² A³, which are provided with concentric cylindric flanges a a, which extend outwardly from the heads and form bearing-boxes which engage the spindle B near the ends of the same. The engine shown is provided with roller-bearings between the annular flanges a' and the parts of the spindle engaged by the same. Said roller-bearings consist of inner and outer cylindric sleeves a² a³, rollers a⁴ a⁴, and rings a⁵ a⁶, located at 85 the ends of the rollers for holding the same from shifting endwise. The annular flanges a a' are also shown as provided at their outer ends with attached rings a⁶ a⁷, which project inwardly over the outer ends of the antifriction-rollers and into contact, or nearly so, with the adjacent bearing-surface of the spindle B. The spindle B is provided in its part between the cylinder-heads A² A³ with an eccentric cylinder or drum E, which is rigidly attached to 90 and preferably made integral with the end portions of the spindle at either side thereof. 95 100

Said eccentric cylinder E is made of such size and so located that its part of greatest eccentricity, or portion of its surface at the greatest distance from the central axis of the 5 spindle of which it forms a part, comes in contact with or bears against the inner cylindric surface of the casing A. At its ends the said eccentric cylinder is provided with two outwardly-extending rigidly-attached 10 disks or flanges E' E', which are concentric with respect to the spindle B and fit at their margins against the inner cylindric surface of the exterior casing A, the two disks or flanges thus formed constituting, in effect, the 15 side walls of the interior space or chamber of the motor. To afford a tight joint between the margins of the said disks E' E' and the surrounding casing, said casing is shown as provided with two packing-rings F F, which 20 are clamped or held in place by being inserted between the ends of the cylinder A' and the marginal parts of the cylinder-heads A² A³. In the particular construction illustrated the ends of the cylinder A' are grooved or rabbeted to receive the outer margins of the 25 packing-rings, which latter project inwardly from the inner surface of said cylinder, so as to overlap the margins of the disks E' E' and bear against the outer faces thereof. This 30 construction leaves a slight space between the said disks E' and the adjacent inner faces of the heads A² A³.

The casing A is provided with two oppositely-arranged radially-movable flat pistons 35 G G of rectangular form, located in a plane passing through the axis of rotation of the casing and of proper width to fit closely between the disks E' E', which form the side walls of the interior space or chamber of the 40 casing. Said pistons slide at their outer ends in guide-recesses formed in radial extensions on the casing A, said extensions consisting, as herein shown, of integral projecting parts A⁴, Fig. 3, on the cylinder A, and hollow U-shaped castings A⁵, Figs. 17 and 18, attached 45 to said extensions A⁴ A⁴ and provided with flat side covers or heads A⁶ A⁶, which form the end walls of said guide-recesses for the sliding pistons. Packing-strips a are shown 50 as located in grooves formed in the inner ends of the castings A⁵, so as to bear against the side faces of the piston and prevent leakage of steam at these points. The said sliding pistons G bear constantly at their inner ends against the exteriorly-cylindric surface of the cylinder E and are held in contact with said cylinder by means of suitably-applied springs, herein shown as having the 55 form of coiled springs H, which are located 60 in said guide-recesses and which bear against the outer ends of said pistons. Said springs are shown as placed around guide-pins H', which are secured at their outer ends in the castings A⁵ and slide at their inner ends in 65 guide-passages g, formed in the said pistons G. In order to insure the maintenance of a steam-tight joint between the sliding pistons

G and the eccentric cylinder E, said sliding pistons are provided with shoes I, which have oscillatory connection with the inner edges of the pistons in such manner that said shoes may turn or swing slightly to maintain the proper angular relation between the same and the eccentric as the pistons move or turn around the eccentric with the shoes in contact therewith. The cylinder A is shown as provided with recesses a⁹ at the inner ends of the guide-openings for the pistons to receive the shoes I when the pistons are at their extreme outward position. 70 75 80

The pivotal connection between the shoe I and the body of the sliding pistons G is shown as formed by means of a longitudinal cylindric head g', Fig. 6, on the inner edge of the piston, engaged by the correspondingly-shaped longitudinally-shaped recesses i in the said shoe I. 85

In order to insure a tight joint between the eccentric cylinder E and the inner surface of the surrounding cylinder A' and to compensate for wear on the inner surface of the said cylinder, the said eccentric cylinder is shown as provided with a movable packing-strip J, which slides radially in a suitable longitudinal recess in the cylinder and which is forced 95 outwardly against the inner surface of the cylinder A' by means of suitably-applied springs j. 90

The cylinder E is provided with inlet and outlet ports e e', which open through the surface of the cylinder at either side of the line of contact between the same and the surrounding cylinder A'. Said ports e e' communicate with longitudinal passages e² e³, which extend through the body of the cylinder E and the 100 spindle B to points outside of the bearing-flange a on the rotating casing, where said passages turn outwardly and are connected with radial openings e⁴ e⁵ in the spindle. 105

K is a casing secured rigidly to the spindle 110 B, around the part thereof in which the openings e⁴ e⁵ are located. Said casing is provided with a cylindric seat for a valve L and with lateral passages k k, leading from ports in the valve-seat of the valve L to the openings 115 e⁴ e⁵ at the sides of the spindle B. Said casing K is also provided with a centrally-arranged exhaust-passage k², leading from a port in the seat of said valve L and connected with an exhaust-pipe M. The casing K is 120 also provided with an inlet-passage k³, with which is connected a steam-supply pipe K'. The valve L is so arranged that by rotation on its axis either of the passages K' K² may be brought into connection with either the inlet-port k³ or the exhaust-passage k², so that the valve constitutes a reversing means by which the motor may be driven in either direction. The valve L is shown as provided with a hand-lever L', by which it may be turned 125 for reversing the engine. 130

In the operation of a motor constructed as above described the steam, compressed air, or gas enters the casing through one of the

ports e or e' and is exhausted through the other of said ports. Assuming the ports to be in the position shown in Fig. 3, the pressure produced in the casing at one side of the plane of the two pistons G G , acting on the piston which is in an advanced position, (the upper piston in the drawing,) serves to turn or rotate the casing, the exhaust passing from the space at one side of the plane of the sliding piston at the time that the space at the other side of such plane is subjected to pressure. When by the turning of the casing each of the pistons passes the inlet-port, pressure will begin to act upon the same, so that 15 said pistons come into action alternately and the exhaust takes place from the spaces at the opposite sides of the plane of the piston successively, it being obvious that the spaces or chambers at opposite sides of said plane 20 will become alternately pressure and exhaust spaces as the casing continues to revolve. To maintain always a steam-tight joint between the side edges of the pistons G and the sides of the guide-passages and the disks E' , 25 a construction is provided which is shown in detail in Figs. 8 to 13, the same being as follows: The said piston G is divided longitudinally into two sides or halves G' G^2 , which are connected at their meeting edges by means of 30 a sliding and steam-tight connection, consisting of a tongue g' on one part and a groove g^2 in the other part to receive said tongue. Coiled springs g^3 are inserted in recesses in the part G^2 , so as to act upon the inner end 35 of the tongue g' to throw or separate the two parts of the piston, and thus hold their outer edges pressed against the inner faces of the disks E' E' . At the outer end of the piston plates g^4 g^5 are applied to the edge of the 40 parts G' G^2 , the plate g^4 terminating short of the inner edge of said part G' , while the plate g^5 extends beyond the end of the part G^2 to form a projecting arm g^6 , which overlaps the adjacent edge of the section G' to 45 prevent the escape of steam along the grooves formed by the separated edges of the parts of the piston. The shoe I at the inner end of the piston G is also made longitudinally expandible, so that its ends may be held in contact with the disks E' E' in the same manner as the body of the piston. The construction for this purpose is shown in Figs. 10, 11, 12, and 13. As clearly shown in these figures, said shoe I is made in two parts I' I^2 . The 50 part I' is provided between the longitudinal groove and its contact-face with a projection i , which enters a corresponding slot or recess i' , formed in the part I^2 . The tongue i is preferably made tapered transversely, with 55 its wider end adjacent to the recess of the shoe and its narrower edge adjacent to the bearing-face of the shoe, as clearly shown in Figs 12 and 13. Spiral springs i^3 are placed in recesses in the part I^2 and bear against the 60 part I' , said springs tending to throw the said parts away from each other, and thus hold their ends in contact with the disks E' E' .

In Figs. 14, 15, and 16 I have shown a somewhat-different construction in the piston G . In this case the piston consists of one main 70 piece or plate and two lateral bars G^3 G^3 , having tongue-and-grooved connection with the body of the plate in the same manner as before described in connection with the two-part construction illustrated in Figs. 8 and 9. In 75 this instance, however, each of the bars G^3 is provided at either side of the tongue g^7 thereon with two lugs g^8 g^8 , arranged parallel with the tongue and separated therefrom, said tongues engaging shallow recesses g^9 g^9 80 in the side faces of the body of the piston, said lugs holding the bars G^3 from endwise movement with respect to the body of the piston.

In Figs. 19, 20, 21 and 22 I have shown a 85 construction in which the exterior casing of the motor is stationary and in which is provided a cut-off valve, whereby the steam may be used expansively in a single engine, and also a construction whereby two motors, 90 made as hereinbefore described, may be connected to form a compound engine. In this instance N N' indicate two motors, the casings of which are stationary, but are in their main features like those hereinbefore described in Figs. 1 to 5 and which are connected with and operate a single shaft N^2 . The two motors N and N' being alike, one of them will now be described, the same being shown in section in Figs. 21 and 22. Said 100 motor embraces a casing O and a spindle P , which is attached to and turns with the shaft N^2 , which connects the spindle of the two motors with each other. The spindle P turns in the casing and is provided with an eccentric cylinder Q , which cylinder corresponds in all respects with the cylinder E , hereinbefore described. Said casing O embraces a cylinder O' and heads O^2 O^3 . The head O^2 is in this instance provided with two annular passages o o' , arranged side by side and located between the cylinder Q and the annular bearing-flange O^2 on said head, which affords bearing for the outer end of the spindle P . The cylinder Q is provided with two 110 ports, which are connected by longitudinal passages q^2 q^3 with inlet and outlet ports q^4 q^5 , which latter ports are arranged out of circumferential line with each other and in such positions that one coincides with the annular passages o' and the other with the annular passages o . R R' are steam supply and exhaust passages, which are attached to the head O^2 and communicate one with the annular passage o and the other with the annular passage o' . The construction described, embracing the head O^2 , provided with the passages o o' , obviously affords a means of providing separate supply and exhaust connections with the ports of the eccentric cylinder, notwithstanding the fact that the said cylinder and its connected spindle revolve within the casing. A motor thus constructed 120 obviously operates in the same manner as

that hereinbefore described, the fact that the casing is non-rotative and that the spindle and eccentric cylinder rotate making no difference in the action of the operative parts.

- 5 Now referring to the cut-off valve, whereby steam is admitted intermittently instead of continuously to the engine-casing, so that it may operate expansively, the motor N, Figs. 19 and 20, is provided with a reversing-
 10 valve embracing a valve-casing R² and a rotative valve-closure r, said reversing-valve operating substantially in the same manner as the reversing-valve shown in Fig. 4. The valve-casing R² is provided with an inlet-
 15 passage r' and an outlet - passage r². Between the steam-supply pipe S and the inlet-
 passage r' of the reversing-valve is located a cut-off valve (indicated as a whole by T) and embracing a cylindric valve-casing T', herein
 20 shown as made integral with the valve-casing R² of the reversing-valve and containing a cylindric valve-seat which is in open communication with the said inlet-passage r'. In said valve-seat is located a hollow piston-
 25 valve U, which slides endwise therein and is operated through the medium of an eccentric U' and eccentric-straps U² from the shaft N² of the engine. The hollow piston-valve U is open at its inner end and closed at its outer
 30 end and provided with a lateral port u, which is located at a distance from the open end of the piston-valve somewhat greater than the diameter of the port s, through which the steam is admitted to the valve-casing T'.
 35 These parts are so arranged that when the eccentric is at one limit of its stroke the valve will be moved outwardly in the casing so as to bring its inner end outside of the valve-
 port s, thereby permitting steam to pass in-
 40 wardly to the cylinder and casing, and when the eccentric is at the outer limit of its stroke the port u will come opposite the port s, and thereby admit steam through the hollow valve to the casing. The movement of the said
 45 valve will be so adjusted with respect to the rotation of the eccentric cylinder E that steam will be admitted twice at each revolution of the eccentric and just after the admission-
 port e e' passes one of the two pistons G G,
 50 the effect being that steam will be admitted at the desired length of time after the admission-port has passed the piston, but will be cut off before the eccentric has completed a half-rotation, thereby permitting the steam
 55 to act expansively during the latter part of each half-rotation, during which the steam is acting upon one of the two pistons.

Now referring to the construction whereby the two motors N N' are adapted to act as a compound engine, features are shown in said Figs. 19, 20, and 21, as follows: The motor N' is provided with a reversing-valve V, made like the valve R² and embracing a casing V' and a rotating valve-closure v. Supply and
 60 exhaust pipes R R' lead from the valve-casing V' to the engine-casing in the same manner as before described in connection with

70 the motor N. The outlet-port r² of the casing R² belonging to the motor N is connected with the inlet-passage v² of the corresponding casing belonging to the motor N' by means of a pipe W. To provide for simultaneous actuation of the two reversing-valves R and V, the valve-closures r and v are connected to a common actuating-shaft X, which is provided with a hand-lever X', through which it may be turned or rotated.

75 Manifestly in the operation of the two motors N N' the exhaust from the first motor N passes to the supply-port of the second motor N' and is used expansively in the second motor in the same manner as in compound steam - engines of the reciprocating piston type.

80 I claim as my invention—

85 1. In a rotary motor, an axle or shaft having two concentrically-disposed flanges thereon, a drum eccentrically fixed between said flanges, a cylinder inclosing the space around the drum between the flanges and having bearing on the shaft or axle outside of the flanges, and movable plates held against the surface of the drum and fitting closely between said flanges.

90 2. In a rotary motor, an axle or shaft having two concentrically-disposed flanges thereon, a drum eccentrically fixed between said flanges, a cylinder inclosing the space around the drum between the flanges and having bearing on the shaft or axle outside of the flanges, and movable plates held against the surface of the drum and fitting closely between said flanges, said shaft and drum being provided with inlet and outlet passages and communicating with the chambers in the 95 casing formed between said plates.

95 3. In a rotary motor, an axle or shaft having two concentrically-disposed flanges thereon, a drum eccentrically fixed between said flanges, a cylinder inclosing the space around the drum between the flanges and having bearing on the shaft or axle outside of the flanges, and movable plates held against the surface of the drum and fitting closely between said flanges, said shaft and drum being provided with inlet and outlet passages and communicating with the chambers in the 100 casing formed between said plates, and a steam-chest on said shaft outside said casing and a valve in said chest for controlling the 105 passage of the motive agent through said inlet and outlet passages.

105 4. In a rotary engine, an eccentrically-disposed fixed drum, concentrically - disposed flanges at opposite ends of said drum, a cylinder or casing inclosing the space around the drum and between the flanges and movable pistons held against the surface of the drum by yielding pressure and closely fitting between the flanges.

110 5. In a rotary engine, a fixed axle or shaft having two concentrically-disposed flanges thereon, a drum eccentrically fixed between said flanges, a cylinder or casing inclosing

the space around the drum and between the flanges and having bearings on the shaft or axle outside of the flanges, and movable pistons held against the surface of the drum by yielding pressure and fitting closely between the flanges.

6. In a rotary engine, a fixed axle or shaft having two concentrically-disposed flanges thereon; an eccentrically-disposed drum fixed between said flanges; a cylinder or casing comprising an annular part closing the space around the drum between the flanges and side plates secured to the annular part and engaging outside of the flanges on the axle; and movable pistons held against the surface of the drum by yielding pressure and fitting closely between the flanges.

7. In a rotary engine, a fixed axle or shaft having two concentrically-disposed flanges thereon; an eccentrically-disposed drum, fixed between said flanges; a cylinder or casing comprising an annular part closing the space around the drum between the flanges and side plates secured to the annular part and engaging outside of the flanges on the axle; antifriction-bearings interposed between the inner edges of the side plates and the axle or shaft; and movable pistons held against the surface of the drum by yielding pressure and fitting closely between the flanges.

8. In a rotary engine, a fixed axle or shaft having two concentrically-disposed flanges thereon; an eccentrically-disposed drum between said flanges; a cylinder or casing comprising an annular part closing the space around the drum between the flanges and having slots or openings therethrough; hol-

low caps or extensions secured to the annular part over said slots, and side plates secured to the annular part and engaging outside of the flanges on the axle; and pistons radially movable in the slots and hollow caps.

9. In a rotary engine, an eccentrically-disposed drum; a cylinder inclosing a chamber about the drum and having a hollow extension thereon, a piston movable in said extension and consisting of two or more parts, means for pressing the parts apart in opposite directions against the end wall of the chamber, and coiled springs seated in openings in the outer end of the parts of the piston for forcing the inner edge thereof against the drum with yielding pressure.

10. A rotary motor comprising an exterior casing having a cylindric interior surface, an eccentric cylinder therein, said cylinder and casing having rotative movement one with respect to the other, radially-sliding plates mounted in the casing and engaging the surface of the eccentric cylinder, and supply and exhaust passages leading through said eccentric cylinder and opening into the interior of the casing, said plates having oscillatory shoes, and both the plates and shoes being laterally expandible.

In testimony that I claim the foregoing as my invention I affix my signature, in presence of two witnesses, this 1st day of March, A. D. 1901.

BASIL V. SZABÓ.
